US00D845920S

(12) **United States Design Patent** (10) **Patent No.:** **US D845,920 S**
(45) **Date of Patent:** **** Apr. 16, 2019**

(54) **PORTION OF LIGHT-EMITTING DIODE UNIT**

(71) Applicant: **EPISTAR CORPORATION**, Hsinchu (TW)

(72) Inventor: **Min-yen Tsai**, Hsinchu (TW)

(73) Assignee: **EPISTAR CORPORATION**, Hsinchu (TW)

(**) Term: **15 Years**

(21) Appl. No.: **29/623,528**

(22) Filed: **Oct. 25, 2017**

Related U.S. Application Data

(60) Continuation-in-part of application No. 29/595,081, filed on Feb. 24, 2017, now abandoned, which is a division of application No. 29/554,553, filed on Feb. 12, 2016, now Pat. No. Des. 782,428.

(57) **CLAIM**

The ornamental design for a portion of light-emitting diode unit, as shown and described.

DESCRIPTION

FIG. 1 is a perspective view of a portion of light-emitting diode unit showing our first example of the new design; FIG. 2 is another perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; and FIG. 8 is a bottom plan view thereof.

FIG. 9 is a perspective view of a portion of light-emitting diode unit showing our second example of the new design; FIG. 10 is another perspective view thereof; FIG. 11 is a front elevational view thereof; FIG. 12 is a rear elevational view thereof; FIG. 13 is a left side view thereof; FIG. 14 is a right side view thereof; FIG. 15 is a top plan view thereof; and, FIG. 16 is a bottom plan view thereof.

The broken lines in the drawing depict portions of the light emitting diode unit that form no part of the claimed design.

1 Claim, 10 Drawing Sheets
